UNITED STATES PATENT OFFICE

1,928,849

AUTOMATIC AND SEMIAUTOMATIC TELEPHONE PLANT

Douglas Cormack Crowe, Stockholm, Sweden, assigner to Telefonaktiebolaget L. M. Ericsson, Stockholm, Sweden, a company of Sweden

Application July 7, 1930, Serial No. 466,266, and in Sweden July 9, 1929

4 Claims. (Cl. 179—27)

The present invention relates to switching arrangements in automatic and semi-automatic telephone plants. More particularly the invention relates to such plants in which both ordinary talking connections and privileged or preferred calls, by way of example inter-office connections, may be established over the same selectors. The invention is substantially characterized in that the test circuits of the selector, at 10 the setting of the selector in a definite position, are automatically shifted in such a manner that the connection may be established with a wanted line even when the latter is engaged by a conversation which is not an inter-office one. The setting of the selector in said position is preferably brought about by an additional impulse series which has no correspondence in the subscriber's number the system being then arranged in such a manner that the selector, after it has been set 20 by said impulse series in the position in question and caused shifting of the test circuit, is automatically restored to the starting position so that it thereupon may be set in ordinary manner by a new impulse series. The shifting position in 25 question may be any one of the setting positions of the selector. Preferably the selector is provided with an additional setting position so that the normal capacity of the selector is not reduced. In selectors having, by way of example, ten setting positions in one or more directions an eleventh setting position is thus preferably provided, the setting of the selector in this position then being brought about by an impulse series comprising eleven impulses. At the same time 30 35 the advantage is gained that a setting of the selector in the shifting position in question cannot be brought about by means of those impulse senders which are ordinarily employed in subscriber's sets as said senders are adapted to send at most ten impulses in each series. On the other hand, the impulse sender of the inter-office operator may easily be made in such a manner that the required number of impulses may be sent.

The additional impulse series intended to bring about the shifting of the testing circuit must, of course, be sent in each point of the talking connection where an inter-office call should be preferred. If the operator has a finger disc, she 40 45 sends consequently by means of said disc an additional impulse series at each occasion when preference is wanted for an inter-office call. If the operator has a register and a key set the sending of the additional impulse series may take 50 55 place automatically by a special marking by

means of a key in connection with the registration of the subscriber's number.

If the additional impulse series in question comprises a number of impulses which could be reproduced by the subscriber, special measures 60 must be taken to prevent that a subscriber having knowledge of the system may be able to establish an undue connection. For this purpose special measures are taken, according to the invention, so that upon setting the selector 65 in the shifting position in question a current impulse or a signal is sent to switching members disposed at the calling end of the talking connection which members may interrupt the connection or prevent its completion. The system is arranged 70 in such a manner that said impulse or signal is inoperative at inter-office communications established from an inter-office operator but, on the other hand, will be operative at all communications established from a subscriber or another 75 undue calling place.

By the above described arrangements it is rendered possible, as mentioned above, to establish an inter-office connection with a subscriber even if he for the time being is engaged by a communication not being an inter-office one. The inter-office operator may then at will break the already established connection which may take place either automatically immediately upon the connection to the subscriber's line or through a 80 special switching operation after effected connection whereby the operator has a possibility to inform the subscriber before the connection is interrupted. At the connection the subscriber's 85 line is marked engaged for inter-office communication, by way of example, by a direct earthing of the c-wire so that the inter-office communication may not be disturbed by another inter-office call. If the subscriber already before is engaged by an inter-office communication another inter-office operator may thus not obtain 90 connection. Instead said operator receives a signal indicating that the subscriber is engaged by 95 an inter-office communication.

When the called subscriber after completed call 100 rehooks the micro-telephone a signal is generated which is repeated back and causes a clearing signal at the operator's position. Said signal is removed if the subscriber again lifts off the micro-telephone. The subscriber may in this 105 manner call the operator's attention without interrupting the communication. After the subscriber has completed the conversation by rehooking the micro-telephone the operator may again call the subscriber when required. 110

The invention will be more closely described with reference to the accompanying drawings showing a part of a talking connection established over two telephone exchanges. Figure 1 shows the relays in circuits appertaining to the outgoing junction line whereas Figure 2 shows a final selector together with the appertaining relays and circuits.

A calling subscriber may in a manner known per se obtain connection from his apparatus A to a junction line FL extending to another telephone exchange over his subscriber's line AL and one or more selectors. In the shown example only the contact arms of a call finder AS and a group selector GV are shown. The junction line FL and the appertaining relay set are connected to the contact field of the group selector through a junction AFL consisting of four wires a, b, c, d, and also to the inter-office operator's desk EP through a similar quad-wire junction line EFL. The junction line FL is in usual manner provided with a relay RA included in the microphone circuit of the calling subscriber which relay at its contact 1 controls the circuit extending over the junction line which circuit in usual manner is separated from the microphone feeding circuit of the subscriber by condensers Ka, Kb. The circuit extending over the junction line contains a winding of a relay RD included between the two line branches which winding is adapted to be short-circuited during the impulse sending over a contact 2 of a relay RW. Said blocking of the subscriber, unduly trying to establish communication with another subscriber, is brought about in the shown example by short-circuiting the impulse contact 1 of the relay RA, the short-circuit being established over a contact 3 of a relay RB actuated by the blocking impulse sent from the final selector. If the call is sent from an inter-office operator, no efficient blocking takes place because the short-circuit is of a very short duration. If, on the other hand, the call is sent from a subscriber unduly trying to establish the desired communication a durable blocking is obtained as the relay RS is then locked in energized position. The holding circuit of the relay RB is for this purpose controlled by a relay JBR actuated only upon calls from an operator's position and which at its contact 4 interrupts said holding circuit but upon calls from a subscriber remains inoperative and consequently causes blocking.

The line selector LC, Figure 2, consists in the shown example of a relay selector of the kind described in the U. S. Patents Nos. 1,645,897 and 1,659,627. The selector comprises a so called multiple relay provided with ten relay armatures and a corresponding number of contact spring groups KS actuated by said armatures and a magnetic circuit common to all armatures and provided with a magnet winding CM which is throughout wound in the same direction on one and the same magnetic core and at both ends connected to the negative pole of the central battery. At the points designated by the numerals 1, 2, 3 etc. said winding is provided with tappings over which the magnet winding may be connected to the positive pole of said battery. The selector is adapted to be set by means of impulses over a circuit controlled by the different armatures in such a manner that the armatures are sequentially attracted and released respectively by the influence of the successive impulses. For this purpose the selector is provided with a num-

ber of shifting contacts OK, viz. a group of shifting contacts for each armature which contacts are adapted to control the impulse circuit in such a manner that said circuit is successively extended to the different branching points. The first impulse, incoming at the contact group OK₁, is branched off at the branching point 1 so that the current passes in opposite directions through the parts of the winding CM disposed on opposite sides of said point, a pronounced magnetic pole then being established at the point 1 and the corresponding armature actuated. The system is then so arranged that the contact spring group OK₁ is not actuated before the current impulse ceases. When the impulse has ceased, a shifting takes place so that the impulse circuit is extended to the impulse contact OK₂ and over said contact to the other branching point 2. The other current impulse will consequently bring about a pronounced magnetic pole at the point 2 whereby the other armature is actuated. When the second current impulse ceases the circuit is extended in similar manner to the third shifting contact OK₃ and over said contact to the third branching point 3, the third current impulse will thus actuate the third armature, etc.

In the example shown on the drawings the tenth setting position of the final selector LC is intended to be used for shifting the test circuits of the final selector by an additional impulse series to mark an inter-office call in above described manner. The final selector is for this purpose in the tenth position provided with a contact 5 over which a relay JA may be actuated to bring about said shifting. To mark inter-office calls, relays JB, JD, JE and JG are also provided. The circuit extending over the junction line includes in ordinary manner a relay Ac which together with the relay I serves to transmit the impulses to the final selector. The supply of current to the called subscriber takes place in known manner through the windings of a relay Ac. The disposition of the circuit and the operation of the switching member included therein is, for the rest, readily understood by the following description of the switching operation.

Initially it may be assumed that an inter-office communication has to be established from the operator's position EP. Then a circuit 6 is first closed through the relay RA. At the same time a circuit 7 is closed through the relay JBR which is energized and at its contact 8 closes a circuit of a relay SBR which is also energized. The relay JBR connects the positive pole of the battery over the relay contact 8 to the third wire c of the junction line AFL over a resistance r₁ whereby the junction line PL is marked as engaged in all the selectors R in which the junction line AFL is multiplied. When the relay RA was energized a circuit 10 was closed through a slow-acting relay R₇ which now closes a circuit 11 over the wire d of the junction line EFL whereby said line is marked as engaged. The relay RA has further, at its contact 1, closed the circuit 12 extending over the junction line FL and containing the relays RD and Aa. The former relay connects the relay RQ over a circuit 13. The relay Aa has meanwhile closed a circuit 17 through a slow-acting relay K which in turn has closed the circuit 18 through a slow-acting relay D.

The inter-office operator thereupon sends a series of ten impulses intended to bring about said shifting of the circuits of the final selector. The first current interruption in the line circuit 130

causes de-energization of the relay RA which in turn interrupts the circuit 12 over the junction line. The relay RA at the same time closes a circuit 14 through a relay RV and a holding winding of the relay RD, whereby the latter relay is prevented from being immediately de-energized. The relay RV connects itself into a holding circuit 15 and short-circuits at its contact 2 the operative winding of the relay RD which is now de-energized, after the holding circuit 14 has also been interrupted at the contact 16 of the relay RV. During the impulse sending the relay RQ is de-energized over the circuit 9. On account of the interruption in the junction line circuit now also the relay Aa is de-energized. When the latter relay is de-energized, a circuit 19 is closed through the relay I. The relay K holds its armature attracted during the impulse sending. The relay I closes in turn a circuit 20 through a relay B which is energized. When the relay Aa is again energized the relay I is de-energized a circuit 21 being then formed containing windings of the relay B and C. The relay B is thereby locked in attracted position, whereas the relay C is energized and locks itself over a circuit 22. When the relay I is de-energized a circuit 23 is formed through the magnetizing winding CM of the final selector. As a consequence, the first armature of the selector is attracted. The second current interruption in the line circuit causes now de-energization of the relay Aa, the relay I then again being energized and the relay D being held over the circuit 24. When I is energized the relay B is de-energized, which thereupon remains inoperative. At the same time the circuit 23 of the final selector is interrupted at the contact 25 of the relay I. Then the contact group OK₁ is actuated so that the selector is prepared to receive the second impulse. When the second current interruption ceases and the line circuit is again closed the relay Aa is again energized. Then the relay I is de-energized which now closes a circuit 26 through the second branching point of the magnet winding CM of the final selector. The following current interruptions in the line circuits will now cause an alternate making and breaking of the impulse circuit 26 of the final selector so that the relay armature of the final selector is successively released and actuated.

When the tenth armature of the final selector is actuated a circuit 27 is formed over the contact 5 in the tenth position. The latter circuit includes the operative winding of the relay JA which is now energized and closes a circuit 28 through the operative winding of the relay JE. When thus all impulses have been sent the relay RQ, Figure 1, is de-energized, the circuit 14 through the relay RV being then interrupted. The latter relay is then, as a consequence, de-energized and removes the short-circuit of the operative winding of the relay RD which is then de-energized. Then the relay RQ receives again current over the circuit 13. When the relay I, Figure 2, is de-energized also the relay B is de-energized after a short moment. After another moment also the relay C is de-energized the circuit 22 being interrupted at the contact 29 of the relay D. The relay B is now instead energized over the circuit 18. When the relay C is de-energized, the circuit 27 of the relay JA is interrupted which relay is thus de-energized. The relay C also interrupts the circuit 26 of the final selector at its contact 30 the tenth armature of the selector being then released. At the same

time the relay JE receives holding current over the circuit 31.

The setting of the final selector in the tenth position resulted, as mentioned, in that the relay JA was energized and after a short moment again de-energized. Hereby a blocking impulse is sent back over the talking connection in the following manner: When the relay JA is energized a short-circuit is established at the contact 32 of said relay over the two branches of the junction line whereby the relay RD is de-energized. Then a circuit 33 is closed through a relay RY which is now energized and closes a circuit 34 through two relays Ra and Rb. The latter relays are energized and connect themselves into a holding circuit 35. Then a circuit 36 is closed through the relay RS which now is energized and short-circuits the impulse contact 1 of the relay RA. Said blocking impulse is repeated by the relay RB by short-circuiting both talking line branches of the junction line EFL over the contact 37 of the relay B. The blocking impulse causes, however, in this case no blocking because the relay B is again de-energized when the relay JA, Figure 2, is de-energized. When the relay RB is de-energized the circuit of the relay RQ was interrupted which after a moment is de-energized the circuit 36 being then interrupted and the relay B de-energized. When the relay JA, Figure 2, is de-energized, the short-circuit of the junction line is removed and the relays RD and RQ are again energized. The relay RD then interrupts the holding circuit of the relay Ra and Rb which are thus de-energized.

The final selector may now be set by means of a new impulse series to bring about connection to the wanted subscriber's line BL. The setting of the final selector takes place in above described manner. It is assumed that the selector is then set in the seventh position. After all the impulses have been sent the relay D is de-energized a circuit 38 being then formed through a relay P which is de-energized and locks itself over a circuit 39. When the relay D is de-energized also a test circuit 40 is closed over the third wire c and the calling subscriber's cut-off relay BR which circuit also includes a winding of the test relay JG.

Initially, it may be assumed that the calling subscriber is not engaged by any conversation. The relay JG will then be energized, said relay then connecting itself into a holding circuit 41. In the latter circuit the relay JD is parallel connected with the holding winding of the relay JG for which reason also the relay JD is de-energized. The latter relay interrupts at its contact 42 a short circuit 43 over the operative winding of the relay G the relay G then being energized and locking itself over a circuit 44 including the cut-off relay BR. The relay G closes at the same time a circuit 45 through a buzzer current source RT to mark the calling signal which circuit includes a winding of the relay Ac through which a signal current is induced in the line circuit. When the relay C after a moment drops its armature the circuit 31 is closed through the relay JE. When the relay JE in turn is de-energized after a moment a holding circuit 46 is closed through the holding winding of the relay G. At the same time the c-wire is connected to earth over a current path 47 whereby the subscriber is marked as engaged by an inter-office call.

When the relay JE is de-energized a calling circuit 48 is closed over the called subscriber's line which circuit includes a calling current source

- 5 RGI sending a calling signal particularly adapted for inter-office calls. Said circuit includes also the two windings of the relay R which, however, is not actuated by the calling current so long as the called subscriber has not answered. When the subscriber answers by lifting the micro-telephone the calling current is amplified through the relay R so that said relay is energized, the circuit 39 of the relay P being then interrupted.
- 10 When the relay P as a result is de-energized the calling circuit 48 and the buzzer circuit 45 are interrupted. The relay R locks itself over the circuit 49. When the subscriber answers his microphone circuit 50 is closed through the relay Ac which at its contact 51 connects the one winding of the relay Aa to the a-branch of the junction line. By this the talking connection is completed.
- 15 When Ac is energized a circuit 52 is closed through the relay JF which is energized and interrupts the circuit of the relay R at its contact 53 whereby the relay R is de-energized. During the time of the relay R being energized the b-branch of the junction line is directly connected to earth over the circuit 54. Thereby a signal is sent back to the calling end of the talking connection in the following manner. The relay RD is de-energized because the two branches of the junction line now are connected to earth.
- 20 Then the circuit 33 is again closed through the relay RY which is energized and connects the two relays Ra and Rb to the two branches of the junction line. In this case only the relay Ra is, however, actuated, which relay now closes a circuit 55 through the relay RM. The latter relay is energized and connects the b-wire of the junction line EFL to earth at its contact 56 whereby the signal is thus repeated through the operator's position, where it may be used to actuate a signalling lamp whereby the operator is informed that the called subscriber has answered. At calls from a subscriber said signal may instead be used to actuate the call meter to register the call.
- 25 When the called subscriber after completed conversation rehooks the micro-telephone, the relay Ac is de-energized. The latter relay then interrupts at its contact 51 the connection between the positive pole of the battery and the a-branch of the junction line whereby a signal is sent back to the calling end of the connection in the following manner. The relay D is de-energized and connects the relay RY into circuit which connects the two relays Ra and Rb to the junction line. In this case only the relay Rb is actuated and closes a circuit 57 through a relay RC which at its contact 58 brings about a corresponding interruption in the a-branch of the junction line EFL. The signal transmitted in this manner is utilized to actuate a clearing signal at the operator which is thus informed that the called subscriber has completed the conversation. When the relay Aa is de-energized a circuit 59 is closed through the relay P.
- 30 The operator may now again call up the subscriber, for instance by sending an impulse over the line circuit by means of the finger disc. When the relay Aa as a consequence is de-energized the relay JF is de-energized, because the holding circuit of said relay is interrupted at the contact 60. Consequently the inter-office calling circuit is now again closed over a contact of the relay JF and the subscriber is again called up. When the subscriber answers by lifting the mi-

cro-telephone the calling signal is disconnected as before.

If the subscriber is assumed to be engaged by a conversation which is not an inter-office one the following switching operation will take place after all the current impulses have been sent. When the relay D is de-energized the relay P is de-energized as before. The testing relay JG receives also now sufficient current to be energized because it is now parallel connected with the resistance included in the testing circuit of that line with which the subscriber's line now communicates. The relay JG is consequently energized, also the relay JD being in above described manner operative. When the latter relay now interrupts the short-circuit over the relay G said relay receives, however, not sufficient current to be able to attract its armature, because the test relay in the already existing connection is included as a shunt across the test circuit in question. When the relay G after a moment is deenergized a circuit 61 is formed through the relays JA and JB which are energized. The relay JB locks itself over its contact 62 and the contact 60 of the relay Aa. The magnetizing circuit of the final selector receives now holding current over a contact of the relays K and JG and over the resistance F. When the relay JB is energized also the relay R is connected into circuit over the contact 63 of the relay JB the relay R then locking itself over its contact 64 and the contact 53 of the relay JF. When R is energized the circuit through the relay P is interrupted at the contact 65. When the relay, as a consequence, is deenergized the circuit through the relay JA is interrupted at the contact 66 of P 105 for which reason also the relay JA after a moment is de-energized. During the time of the relay JR being de-energized the junction line is short-circuited at the contact 32. Hereby a signal is received as before which is repeated back and 110 whereby the subscriber is informed that the connection is completed. The subscriber is now over the condensers Ca and Cb and the contacts 67, 68 of the relay JB connected to the already existing connection so that the operator may communicate with the wanted subscriber.

When the connection has to be interrupted this may be effected by that the operator, by way of example, by means of her finger disc brings about one or more current interruptions in the line circuit. When the relay Aa, as a consequence, is de-energized the circuit of the relay JB is interrupted at the contact 60 of the relay Aa the relay JB being then de-energized. The relay JE now receives holding current over its contact 69 the 120 contact 70 of the relay JB and the contact 71 of the relay Aa. When the relay Aa is again energized the circuit through the relay JE is interrupted at the contact 71 for which reason the latter relay after a moment is de-energized. Then a circuit 72 of the test relay G is closed. When the relay G, as a consequence, is energized the c-wire is directly connected to earth over a circuit 73 the existing connection being then interrupted by the test relay of the called subscriber being short-circuited. When the relay G is energized also the relay Ac is connected into circuit over the line circuit the relay JF obtaining current over the circuit 52. Then the circuit through the relay R is interrupted at the contact 53 whereby the relay R after a short moment is de-energized. When the relay G is energized also the b-wire of the junction line is connected to earth over a contact 75 of the relay G and the contact 76 of the relay R whereby an answering signal is received 150

which ceases when R is de-energized and which is repeated to the operator. The inter-office communication is thereby completed.

If the called subscriber already is engaged by an inter-office conversation the c-wire is directly connected to earth. When the relay B after completed impulse sending is de-energized the relay JE is thus short-circuited. The relay P is de-energized as before and, a buzzer circuit for busy-marking is closed through the buzzer winding of the relay Ac over the contact 77 of the relay P and the contact 78 of the relay G through a buzzed current source BT. When the relay C after a moment is de-energized also the relay JE is de-energized. The connection is then cleared through interruption of the line circuit.

It may now be assumed that the subscriber A unduly tries to establish a communication with another subscriber by sending an additional series of impulses. The switching then proceeds in substantially the same manner as above described as regards calls from an inter-office operator's position with the difference that in this case only the relay SBR is actuated whereas the relay JBR remains de-energized. After sending the first impulse series a blocking signal is sent back, as in the former case, over the junction line by that the relay JA for a moment short-circuits both branches of the junction line. Then the relays Ra, Rb are actuated in above described manner which relays in turn close the circuit 36 of the relay RB. When the latter relay is energized it connects itself into a holding circuit 79 which remains closed so long as the calling subscriber holds his micro-telephone lifted. The relay Rb short-circuits at its contact 3 the impulse contact 1 of the relay Ra whereby all further impulsing from the subscriber is prevented.

The invention may, of course, also be applied in systems having mechanical selectors, by way of example such group and final selectors which may be set in one direction to select the wanted line group and in another direction to select the wanted line. In selectors of the latter kind the arrangement is preferably disposed in such a manner that the shifting of the test circuit is brought about by a preparatory setting of the selector to a certain position in the motion direction in which the selector is set at first to select the desired line group whereupon the selector is restored to be able to be set anew to select the wanted line group. If the first setting position is used as shifting position the selector needs not be restored but it may be set anew from said position as a starting position.

I claim:—

1. In a telephone system in which ordinary talking connections and so-called privileged or preferred connections, by way of example inter-

office connections, may be established over the same selectors, a telephone line, a selector connected thereto, switching elements appertaining to the selector, means to actuate said switching elements to shift the test circuits of the selector automatically so as to allow establishing of a communication with a line also when the latter is engaged by a conversation which is not an inter-office one, a bank contact associated with the said switching elements, means to set the selector by a preparatory movement under control of numerical impulses on the said contact so as to obtain the said shifting of the test circuits of the selector before the selector is taken into use for its selecting purpose.

2. A telephone system according to claim 1, in which the selector is provided with a special contact position in which it may be set by means of a series of current impulses comprising more than ten impulses.

3. In a telephone system in which ordinary talking connections and so-called privileged or preferred connections, by way of example inter-office connections, may be established over the same selectors, a telephone line, a selector connected thereto, switching elements appertaining to the selector, means to actuate said switching elements to shift the test circuits of the selector automatically so as to allow establishing of a communication with a line also when the latter is engaged by a conversation which is not an inter-office one, a bank contact associated with the said switching elements, means to set the selector by a preparatory movement under control of numerical impulses on the said contact so as to obtain the said shifting of the test circuits of the selector before the selector is taken into use for its selecting purpose and means to automatically restore the selector to starting position.

4. In a telephone system in which ordinary talking connections and so-called privileged or preferred connections, by way of example inter-office connections, may be established over the same selectors, a telephone line, a selector connected thereto, switching elements appertaining to the selector, means to actuate said switching means to shift the test circuits of the selector automatically upon setting the selector under control of numerical impulses in a definite position, so as to allow establishing of a communication with a line also when the latter is engaged by a conversation which is not an inter-office one, means to restore the selector to starting position, and means to shift the test circuit of the selector by a preparatory setting of the selector to a certain position during the group selecting movement of the selector.
